UNITED STATES PATENT OFFICE

155,558

DESIGN FOR A KITCHEN CABINET

Carl W. Sundberg and Montgomery Ferar, Detroit, Mich., assignors to Sears, Roebuck & Co., Chicago, Ill., a corporation of New York

Application August 28, 1947, Serial No. 141,098

Term of patent 14 years

(Cl. D33—19)

To all whom it may concern:

Be it known that we Carl W. Sundberg and Montgomery Ferar, citizens of the United States and residents of Detroit, in the county of Wayne and State of Michigan, have invented a new, original, and ornamental Design for a Kitchen Cabinet, of which the following is a specification, reference being had to the accompanying drawing, forming a part thereof.

Fig. 1 is a perspective view of a kitchen cabinet embodying our new design.

Fig. 2 is a fragmentary perspective view of a kitchen cabinet embodying our new design.

Fig. 3 is a fragmentary side elevational view of the same.

The dominant feature of our invention lies in the parts shown in full lines in Fig. 1, comprising ing the configuration of the table top and drawer fronts.

We claim:

The ornamental design for a kitchen cabinet, substantially as shown and described.

CARL W. SUNDBERG.
MONTGOMERY FERAR.
